US00D750964S

(12) **United States Design Patent**
Alvarez De Cienfuegos Hernandez et al.

(10) **Patent No.:** **US D750,964 S**
(45) **Date of Patent:** **** Mar. 8, 2016**

(54) **CONTAINER**

- (71) Applicant: **Conopco, Inc.**, Englewood Cliffs, NJ (US)
- (72) Inventors: **Alberto Alvarez De Cienfuegos Hernandez**, Valencia (ES); **Jose Ignacio Lavernia Company**, Valencia (ES)
- (73) Assignee: **Conopco Inc.**, Englewood Cliffs, NJ (US)

(**) Term: **14 Years**

(21) Appl. No.: **29/490,127**

(22) Filed: **May 7, 2014**

(30) **Foreign Application Priority Data**

- Nov. 11, 2013 (EM) 002342931-0001
- (51) **LOC (10) Cl.** **09-01**
- (52) **U.S. Cl.** ..... **USPC** **D9/521; D9/529**
- (58) **Field of Classification Search**
USPC D9/516, 521-522, 529, 530, 541-544, D9/549, 550, 552, 563, 565, 571, 574-575, D9/682, 686, 688, 689, 692, 436, 440, 447, D9/448; 215/382-384; 220/660, 662, 669, 220/675
- CPC B65D 83/00; B65D 35/28; B65D 35/38
